ATTORNEY.

UNITED STATES PATENT OFFICE.

JOSEPH A. WEIL, OF NEW HAVEN, CONNECTICUT.

CORSET.

Application filed April 2, 1924. Serial No. 703,770.

To all whom it may concern:

Be it known that I, JOSEPH A. WEIL, a citizen of the United States, residing at New Haven, in the county of New Haven and 5 State of Connecticut, have invented certain new and useful Improvements in Corsets, of which the following is a specification.

This invention relates to a combined body shaping and reducing garment of the corset 10 and girdle type, and has for its object to provide a garment of the class referred to, in a manner as hereinafter set forth, with means when worn to permit perfect freedom of movement of the wearer and further 15 for concealing the fat of the waist, abdomen, hips and thighs.

A further object of the invention is to provide, in a manner as hereinafter set forth, 20 a garment of the class referred to having means, when worn, to not only reduce the waist of the wearer, but also lengthen the waist line, as well as giving to the body of the wearer an erect, graceful carriage and an appearance of slenderness 25 and youthfulness.

A further object of the invention is to provide, in a manner as hereinafter set forth, 30 a garment of the class referred to, having a resilient body portion acting when worn to exert a massage which is gentle and imperceptible yet powerful in its effect, resulting in the loosening of the fat and at the same time increasing the blood circulation so that the loosened fat is carried from 35 the body of the wearer quickly.

A further object of the invention is to provide, in a manner as hereinafter set forth, 40 a garment of the class referred to, capable of being worn as a corset, at the same time overcoming the discomforts or possible internal harm present when stiff corsets are worn, and enabling the wearer to keep her figure trim and supple, but accomplishing this latter without the uncomfortable feeling 45 of being laced in.

A further object of the invention is to provide, in a manner as hereinafter set forth, 50 a garment of the class referred to, including means for adjustably connecting it in position upon the body of the wearer to reduce the size of the waist without any inconvenience when the garment is worn.

A further object of the invention is to provide, in a manner as hereinafter set forth, 55 a garment of the class referred to, including

means for not only supporting the strained muscles of the side and back of the wearer, but further aiding to strengthen such muscles as well as supporting the great vital organs often out of place in stout persons, 60 as well as enabling such organs to resume their proper positions and to function naturally.

A further object of the invention is to provide, in a manner as hereinafter set forth, 65 a garment of the class referred to, including a resilient body portion adjustably connected together at its rear and having a closed front and further having the intermediate 70 portion of the front cut away to insure conform when the garment is worn, as well as to permit it to fit snugly around the hips and thighs.

A further object of the invention is to provide, in a manner as hereinafter set forth, 75 a garment of the class referred to, comprising a one-piece body portion having an adjustable lacing means, at the back, whereby the wearer can regulate the tightness or looseness with which the garment is to be 80 worn and thereby enable the wearer, as she reduces to take the garment in.

A further object of the invention is to provide, in a manner as hereinafter set forth, 85 a garment of the class referred to, comprising a body portion having its front provided with a stay device to prevent the body of the garment from rolling over at the top, whereby when worn a straight line front effect will be given to the wearer.

A further object of the invention is to provide, in a manner as hereinafter set forth, 90 a garment of the class referred to, comprising a body portion having adjustable back ends provided with stay elements and with 95 these latter so constructed and arranged to prevent the poking thereof into the back of the wearer when the wearer sits down.

A further object of the invention is to provide, in a manner as hereinafter set forth, 100 a garment of the class referred to, comprising a flexible body portion provided with hose supporters and by this arrangement the garment can be substituted for a stiff or other corset.

Further objects of the invention are to provide, in a manner as hereinafter set forth, 105 a combined body shaping and reducing garment, which is simple in its construction and arrangement, strong, durable, resilient, 110

compact, thoroughly efficient in its use, conveniently positioned for use on the body of the wearer, and comparatively inexpensive to manufacture.

5 With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

10 15 In the drawings wherein like reference characters denote corresponding parts throughout the several views:—

Figure 1 is a perspective view showing the adaptation of a garment in accordance 20 with this invention, upon the body of the wearer.

25 Figure 2 is an elevation, looking towards the inner face of the garment with the latter extended, and the lacing removed therefrom.

Figure 3 is a rear elevation of the garment in closed position.

30 Figure 4 is a fragmentary view of one end of the body portion of the garment.

35 Figure 5 is a fragmentary view of a portion of the body portion of the garment illustrating the manner in which a hose supporter is connected therewith.

Figure 6 is a section on line 6—6, Figure 5.

40 Figure 7 is a fragmentary view, in elevation, of the opposed ends of the body portion of the garment.

Figure 8 is a section on line 8—8, Figure 7.

45 Figure 9 is a fragmentary view of the central portion of the front of the body portion of the garment.

Figure 10 is a section on line 10—10, Figure 9.

50 The body portion of the garment, indicated at 1, is constructed from a sheet of resilient material of substantial length and thickness, preferably of "Para" rubber, but it is to be understood that the body portion can be constructed of any suitable material of the desired resiliency, but impervious to moisture. The body portion furthermore is of substantial width so when worn it will 55 extend over the hips and upon the thighs. The front of the body portion 1 has a cut-out part 2 of substantial width and preferably the side edges 3 of said cut-out part project away from each other in a direction 60 towards the top edge of the cut-out part. The cut-out part 2 projects an equal distance from each side of the vertical center of the front of the body portion 1. The cut-out part 2 is of a shape to make the 65 garment comfortable when worn and fur-

ther permits it to snugly fit around the hips and thighs of the wearer in a manner as shown in Figure 1.

The top edge of the body portion 1 is reinforced throughout, as at 4, and which is attained by bending the marginal portion of the top of the body portion 1 upon itself and inherently securing said bent marginal portion to the outer face of the body portion 1.

70 The lower edge of the body portion 1 is reinforced and which is attained by bending the lower marginal portion of said body portion 1 against the outer face thereof and inherently securing the said bent lower marginal portion to the inner face of the body portion 1, as indicated at 5. The lower edge of the body portion 1 is reinforced throughout, in the manner as stated.

75 Each end of the body portion 1 has its outer face provided with a reinforcing strip 6, of substantial width, and which extends from the top edge to the bottom edge of the body portion and further is flush with the said edges, as well as the end edges of the body portion 1. The reinforcing strips 6 are of the same material as the material 80 from which the body portion 1 is formed and are inherently secured in position.

85 The body portion 1, in proximity to each lower corner of the cut-out part 2, has inherently or otherwise secured thereto a substantially rectangular reinforcing piece 7 of suitable length. The pieces 7 are secured 90 against the outer face of the body portion 1 and are furthermore overlapped by the bent lower marginal portions 5 of the body portion 1. The lower marginal portion 5 overlap the bottom and one end of each of the pieces 7.

100 Secured to the outer face of the body portion 1, at the bottom thereof, is a pair of reinforcing resilient pieces 8 of the same material from which the body portion 1 is set up. Each of the pieces 8 is inherently 105 or otherwise secured to the body portion 1 and are arranged between a piece 7 and a strip 6, preferably centrally therebetween. Each of the pieces 8 has its bottom overlapped by the folded lower marginal portion 5. Each of the pieces 8 is rectangular in contour and of substantial length.

110 The bent or folded lower marginal portion 5 of the body portion 1 is secured to the reinforcing pieces 7 and 8.

115 Secured to each of the reinforcing pieces 7 and 8, as well as depending therefrom, is an elastic hose supporter 9. The upper end of each supporter 9 extends into a fabric casing 10, the rows of stitching 11 and 12 120 are employed for connecting the casing 10 to the supporter 9. The row of stitching 11, in connection with rows of stitching 13, 14 and 15 fixedly secured the supporter 9 to a reinforcing piece 7 or 8 and to the body 125 130

portion 1. The rows of stitching 11, 13 and 14, extend through the casing 10, supporter 9, piece 7 or 8 and body portion 1. The rows of stitching 13 and 14 also extend through the supporter 9, piece 7 or 8, bent or folded marginal portion 5 and body portion 1. The row of stitching 15 extends through the supporter 9, bent or folded lower marginal portion 5 and body portion 1. The foregoing arrangement fixedly secures the supporters 9 to the body portion 1. The supporters 9 are arranged in spaced relation, in a manner as shown in Figure 1.

Positioned against the inner face of the front of the body portion 1, centrally thereof, as well as extending from the top to the bottom edge of the body portion, is a strip 16 of fabric of substantial width, and which has the side marginal portions thereof inturned, as at 17. Opposing the outer face of the front of the body portion 1, centrally thereof, is a strip of fabric 18, of a width less than the width of the strip 16. Positioned against the outer face of the strip of fabric 18 is a strip of fabric 19, of the same width and length as the width and length of the strip 16. The side marginal portions of the strip 19 are inturned, as at 20, to overlap the inner face of the strip 18. The sides of the strips 16 and 19 are secured together by rows of stitching 21, and the said rows of stitching 21 extend through the body portion 1, and by this arrangement the strips 16 and 19 are secured to the body portion. The rows of stitching 21 are arranged in proximity to the side edges of the strips 16 and 19. Rows of stitching 22 are employed for securing the strips 16, 18 and 19 together and also for securing the said strips to the body portion 1. The rows of stitching 22 are arranged between the vertical center of the strips 16 and 19 and the rows of stitching 21. Each row of stitching 21 is spaced from a row of stitching 22, and this arrangement provides in connection with the strips 18 and 19 a pair of pockets 23, 24, disposed vertically with respect to the front of the body portion 1. The bottom of the pockets 23 and 24 are formed by a transversely extending row of stitching 25, which is positioned a substantial distance from the top edge of the cut-away portion. The stitching 25 extends through the strips 16, 18, 19 and also through the body portion 1 and further provides means for securing the strips and body portion 1 together. The bottom of each of the pockets is curved, due to the manner in which the stitching is applied. The bottom of each of the pockets is positioned between the longitudinal center and bottom of the body portion 1.

Arranged within each of the pockets is a stay member 26, which extends from the row of stitching 25, to the bent or folded up-

per marginal portion 4 of the body portion 1. The strips 16, 18 and 19, at their top ends, are connected together by stitching 27, and at their lower ends by stitching 28. The stitching 27 extends over the top edge of the body portion 1, and the stitching 28 extends over the bottom edge of the body portion 1.

The providing of the front of the body portion 1 with a stay means, in a manner as referred to, prevents the garment from rolling over at the edges and further gives to the wearer a straight line front.

The garment further includes an adjustable connecting device for securing the body portion 1 in position upon the body of the wearer, and furthermore the said connecting device includes a plurality of stay members and these latter are so set up that they will not poke into the wearer's back when the wearer sits down.

The adjustable connecting device comprises a pair of apertured stay supports, a plurality of stays in each support, and a lacing common to said supports. Each stay support is fixedly secured to one end of the body portion, and as both supports are of like construction the description of one will apply to the other. Each stay support consists of a length of fabric bent upon itself to provide a pair of folds 29, 30. The fold 29 is of greater width than the fold 30 and has the marginal portion, at its free end, inturned upon itself, as at 31. The marginal portion of the free end of the fold 30 is inturned upon itself, as at 32. Extending between the inturned portions 31, 32 of the folds 29 and 30 is one of the reinforced ends of the body portion 1, and when the end of the body portion 1 is arranged in the position just stated, a part 33 of the fold 29 opposes the edge of said end of the body portion 1. The folds 29 and 30, as well as the inturned portions 31, 32 thereof, respectively are secured to the said end of the body portion 1 by spaced rows of stitching 34, which extends through the folds 29, 30, inturned portions 31, 32 and body portion 1. The stay supports project laterally from the end of the body portion 1.

Each of the stay supports further includes a strip 35 of fabric of substantial width, and which has the side marginal portions thereof inturned, as at 36, 37, and seating on the fold 29. Seating on the fold 29 and extending upon the inturned portion 36 of the strip 35 is a flexible strip 38, which also opposes and is spaced from the inturned portion 37 of the strip 35. Seating on a portion of the strip 38 is a flexible strip 39, which is spaced from the remaining portion of the strip 38. The strip 38, in connection with the inturned portion 37 of the strip 35 and the fold 29, provides a stay pocket 40, and the strip 38, in connection

with the strips 35 and 39, provides a stay pocket 41.

The strip 35 and its inturned portion 37, as well as the folds 29 and 30 are secured together by a row of stitching 42. The folds 29, 30 and strips 35, 38 and 39 are secured together by spaced rows of stitching 43. The strip 35 and its inturned portion 36 as well as the folds 29 and 30 are secured together by a row of stitching 44.

Arranged between the pockets 40 and 41 is a row of spaced eyelets 45, which extend lengthwise with respect to the stay supports and further provide means for connecting 15 the folds 29, 30 and strips 35, 38 and 39 together.

The pocket 40 is of less length than the pocket 41, and for this purpose the pocket 41, at a point removed from the upper end 20 of the stay support, is closed by a row of stitching 46.

Each stay support is of a length slightly greater than the width of the body portion 1, and each stay support projects above the 25 top edge and depends from the bottom edge of the body portion 1. The upper ends of the strips which provide the stay support extend into a flexible fabric casing 47, and rows of stitching 48 are provided for securing the casing 47 to the flexible strips whereby the upper end of these latter will be inclosed within the casing, as well as secured thereto. Mounted on and inclosing 30 the lower ends of the strips which provide 35 the stay supports, is a fabric casing 49, secured in position by rows of stitching 50.

Arranged in the pockets 40 of the stay supports are stay elements or members 51, and arranged within the pockets 41 of the 40 stay supports are stay elements or members 52. The elements 52 have their ends terminating at a point in proximity to the casing 48 and 50, and are of greater length than the length of the stay elements 51. The stay 45 elements 52 project upwardly beyond the upper ends of the stay members 51 and also project slightly below the lower ends of the stay members 51.

The lacing for adjustably connecting the 50 stay supports together to provide for securing the garment upon the body of the wearer, is indicated at 53, and which extends through the eyelets 45 in each of the stay supports.

55 Rows of stitching 54 are provided to arrest downward shifting of the stay elements or members. The row of stitching 46 prevents the upward shifting of the stay elements or members 51.

60 By setting up the body portion 1, in the manner as stated, it exerts, when the garment is worn, a massage which is gentle and imperceptible, yet powerful in its effect.

65 This constant and gentle manipulation loosens the fat and at the same time in-

creases the blood circulation so that the loosened fat is carried from the body quickly. Furthermore owing to its resiliency it permits perfect freedom of movement, it also encircles the abdomen, waist, hips and thighs, and owing to its resiliency it overcomes the uncomfortable feeling of being laced in. The providing of the front of the body portion, centrally thereof, with the stay device, not only prevents the body portion from rolling over at the edge but prevents bulging of the abdomen thereby giving to the wearer a straight line front effect, yet said stay device does not cause any inconvenience to the wearer, at any position of the body, whether sitting or standing. The body portion is so shaped that when worn, it conceals the fat of the waist, abdomen, hips and thighs, as soon as it is placed in position, and furthermore it not only reduces the size of the waist, but lengthens the waist line as well, and when worn it gives to the body an erect and graceful carriage.

The body portion further acts to support 90 the muscles of the sides and back without any inconvenience to the wearer, and aids such muscles to become stronger and further acts to enable the great vital organs to resume their proper positions and to function more naturally. Owing to the body portion being resilient throughout it becomes substantially a part of the body of the wearer, bending and instantly adapting itself to any position of the waist, hips and thighs without any inconvenience whatsoever to the wearer.

By constructing the garment with the body portion formed throughout of elastic material and cutting away the lower portion of the front of the body portion substantially in the manner as shown, as well as positioning the hose supporters at the points indicated, when the body portion is in encircling position with respect to the wearer, there will be provided a downward diagonal pull in opposite directions on said body portion, under such conditions causing the snug fit of the garment at the hips and thighs of the wearer.

It is thought that the many advantages of a combined body shaping and reducing garment, in accordance with this invention, can be readily understood, and although the preferred embodiment of the invention is as illustrated and described, yet changes in the details of construction can be had which will fall within the light of the invention as claimed.

What I claim is:—

1. A garment for the purpose set forth comprising a body portion in the form of a split band and formed throughout of elastic material, said body portion having the lower part of its front cut-away and

with the top edge of said cut-away portion extending laterally from each side of the vertical median of the front of the body portion, parallel stay elements secured to 5 the center of the front of the body portion and extending from the top of the latter and terminating a substantial distance above the top edge of said cut-away portion, oppositely extending easings projecting laterally from the ends of said body portion and provided with means for adjustably securing the body portion in position upon the wearer, and a pair of stay members secured within each of said easings, the inner one of the stay members of 10 each pair of stay members having its upper end positioned a substantial distance below the upper end of the outer stay member of the pair to provide a ready flexing of the 15 upper portions of said casings.

2. A garment for the purpose set forth comprising a body portion in the form of a split band and constructed of elastic material throughout, a flexible stay support connected to and projecting laterally from each end of said body portion and provided with a lengthwise row of spaced eyelets, a pair of spaced parallel stay elements arranged within each of said supports and having a row of eyelets positioned therebetween, the outer one of the stay elements of each pair of stay elements projecting a substantial distance above the upper end of the inner stay element of the pair, and a lacing common to said rows of eyelets for adjustably connecting said body portion in position on the wearer. 25 30 35

In testimony whereof, I affix my signature hereto.

JOSEPH A. WEIL.
